UNITED STATES PATENT OFFICE

FRANKLIN LAMB, OF NEW YORK, N. Y., ASSIGNOR TO CARD DISPLAY, INC., A CORPORATION OF NEW YORK

CARD DISPLAY

Application filed April 26, 1929. Serial No. 358,248.

The device of the present invention, while capable of a wider range of embodiments, was primarily designed as an improvement on the sign disclosed in the Bloomingdale Patent No. 1,653,033 dated December 20, 1927, and especially as a means for increasing the commercial value of such signs.

Bloomingdale discloses a changeable character price display sign, peculiarly well suited for use in department stores or other retail establishments where large quantities of goods are displayed on tables or counters in association with a sign indicating the price. The patent shows a convenient method of removably mounting interchangeable price numerals in a backing plate and the present invention aims to provide an effective means for mounting and displaying the assembled carrying plate and numeral bearing units.

In high-class retail stores it is obviously undesirable and slovenly to simply lay the signs about on the counters or to prop them against such supports as may be available and the present invention provides a mounting frame of luxurious appearance which not only aids materially in "dressing" the goods counters, but which holds the signs in position so that they may be readily observed from a distance. The frame is preferably provided with a substantial base of its own so that it may stand upon any suitable supporting surface and the signs are preferably slipped into place through a slot in the frame top.

The invention is further concerned with the provision of a temporary cap piece self-sustaining in applied position upon the frame and adapted to bear decorative matter appropriate to the season. Thus by simply changing the cap pieces the signs will be dressed in accordance with the various holiday seasons or other occasions and without the need for printing special signs for each occasion.

Preferably the cap pieces, when in place, serve to vary the contour of the sign and frame unit and materially alter the general make up of the signs. Preferably also the so-called cap pieces are held in position upon the tops of the frames by tongues which enter

the slots in the tops of the frames and cooperate with the lower edges of the cap pieces to define shoulders which rest upon the frames and limit the insertion of the tongues. Thus the need for any securing means whatsoever is obviated and the decorative cap pieces may be slipped into place or removed in an instant, their expeditious insertion being facilitated by tapering the tongues so that they are automatically self-guiding into place.

Other objects of the invention are to provide a display device of extremely simple, practical construction which will be rugged, durable and efficient in use, attractive in appearance and well suited to meet the requirements of economical manufacture and convenient manipulation.

In the accompanying drawings in which is shown one or more of various possible embodiments of the several features of my invention;

Fig. 1 is a perspective view of a display device embodying the invention,

Fig. 2 is a vertical sectional view therethrough on the line 2-2 of Fig. 1 and on a larger scale,

Fig. 3 is a sectional detail taken approximately on line 3-3 of Fig. 4,

Fig. 4 is a sectional detail on the line 4-4 of Fig. 3 and

Fig. 5 is a perspective view of the removable cap piece.

In the drawings the reference numeral 10 designates an open rectangular frame supported in upright position upon a suitable pedestal 11. The lower cross bar and the sides of the frame are internally channelled as at 12 and 13 respectively and the top of the frame is provided with a slot 14 through which sign cards may be inserted, the edges of these cards lying in the channels.

The card is illustratively of the type disclosed in the Bloomingdale patent above referred to including a plate portion 15 of card board or the like provided with an opening 16 in which removable character bearing elements 17 preferably of the same material and thickness as the plates are inserted and held by stickers 18. In the ordinary course of use

two of the signs are inserted back to back, the channels and slot being wide enough to readily accommodate them.

The ornamental cap piece which is used to dress up the signs for special holiday sales or other unusual occasions is preferably also of cardboard and is of segmental shape, its lower straight edge being preferably equal in length to the length of the upper cross bar 5 of the frame 10. A tapered tongue 20 pendant from the body portion 19 of the cap piece is adapted to enter the slot 14 and lie between the two sign cards which are mounted in the frame. This tongue cooperates 10 with the lower straight edge of the cap piece to define shoulders 21 resting on the ends of the upper frame cross bar beyond the slot so that the cap piece may be applied by the simple expedient of inserting the tongue 20 through the slot 14 and without using any 15 securing devices.

Inasmuch as the tongue fits rather snugly between the two sign cards it tends to hold these cards and the cap piece against rattling 25 or against falling out of place even though the frame be inverted in carrying, and accomplishes this result without injury to the 30 cards or the stickers on their backs.

The particular shape of the cap piece is 35 subject of course to a wide range of variations but it is preferably of a shape which harmonizes with the general shape of the frame 10 and which when in place does not destroy the symmetry of the display. Cap 40 pieces having bodies of triangular, semi-circular, rectangular or trapezoidal formation are all quite effective in use.

By tapering the tongues no "feeling" about 45 is necessary to properly align them with the slot and the tongues automatically guide the cap pieces into properly centered home position.

When a number of the displays are mounted on a counter or on the display tables in a 50 department store and properly dressed with cap pieces bearing appropriate seasonable greetings or seasonable decorations they aid very materially in producing a festive appearance entirely in consonance with the particular occasion which they symbolize or represent. These cap pieces add to the decorative 55 appearance of the sign in any event and they permit a store to be very expeditiously and inexpensively dressed up for purpose of an anniversary sale, Christmas sale, etc.

The cap pieces being of such simple and inexpensive type may be readily stored away 60 for future use after they have served their purpose and the need for revising, or reprinting all of the price cards and other advertising matter on the counters during a special sale or season is entirely avoided.

It will thus be seen that there is herein 65 described an article in which the several features of this invention are embodied, and

which in service attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall 70 be interpreted as illustrative and not in a limiting sense.

Having thus described my invention, what I claim as new and desire to secure by Letters Patent of the United States of America, is:—

1. A display device including a pedestal and an open frame supported in upright position thereon, said frame having a slot in its top through which a pair of sign cards may be inserted and being internally channelled 80 for the reception of the cards, in combination with a decorative cap piece of greater length than the slot resting at its ends upon the top of the frame and including a pendant tongue 85 adapted to enter the slot and retain the cap piece in applied position, said tongue being disposed between said cards.

2. In a display device a sign and a frame therefor, the frame having a slot in its upper edge, a decorative member resting upon the 90 upper edge of the frame and including a pendant tongue lying in the slot, and terminating at its opposite side in shoulders which support said members, and a pair of cards in 95 said frame with the tongue between them.

3. A display device of the character described including a frame having a slot in its top and a pair of oppositely facing sign cards of no greater width than the slot mounted back to back in the frame, a decorative 100 cap piece of a length greater than the width of the slot resting upon the top of the frame and including a pendant tongue extending through the slot and lying between the sign 105 cards.

4. A display device of the character described including a frame having a slot in its top and a pair of oppositely facing sign cards of no greater width than the slot mounted back to back in the frame, a decorative 110 cap piece of a length greater than the width of the slot resting upon the top of the frame and including a pendant tongue extending through the slot and lying between the sign 115 cards, said tongue at its point of junction with the body of the cap piece being of a width approximately equal to the length of the slot whereby to provide supporting shoulders for the decorative cap piece and tapering toward its free end to provide inclined 120 guiding edges.

Signed at New York, in the county of New York and State of New York, this 23rd day of April A. D. 1929.

FRANKLIN LAMB.
